TOP LEAD LOCATOR

Charles John Schnering, Lock Haven, Pa., assignor, by
mesne assignments, to Sylvania Electric Products Inc.,
Wilmington, Del., a corporation of Delaware

Application November 18, 1955, Serial No. 547,642

1 Claim. (Cl. 49—2)

This invention relates to electron tube manufacture and in particular to the sealing in of a top terminal within the dome of a glass envelope.

In certain types of electron tubes it is desirable to provide a terminal lead which shall extend through the dome of the envelope in addition to the circularly arranged leads at the base of the tube. Typical of this class of tubes are the beam power and diode rectifier types wherein an anode lead is led through the dome, although it should be noted that this invention is not restricted to these specific types of tubes. Where a lead does extend through a dome, cracks are apt to develop in the glass if the lead is not centered in the dome. These cracks are due to unequal distribution of the mass of the glass about the lead or to strains on the lead after a cap and connector has been applied to the terminal. Moreover unsymmetrical centering of the top lead is unsightly and renders the article less salable.

This off centering is apt to occur because only the lower end of the lead is fixedly mounted within the tube, the upper terminal of the lead floating through a comparatively large opening in the dome of the unfinished tube. As a consequence, when the glass around the opening is fused down about the terminal there is no certainty that the lead will be axial of the tube.

The object of the invention is to provide a simple means to insure the axial arrangement of the top lead seal with respect to the longitudinal axis of symmetry of the tube.

It is a further object of the invention to accomplish this purpose with as few changes on existing equipment as possible.

These and other objects will be made clear by consideration of the following specification and claim when taken in connection with the accompanying drawings in which:

Fig. 1 is a diagram illustrating the method of sealing the top lead within an envelope as well as the sealing of the bulb to its stem.

Fig. 2 is a fragmental portion of the machine showing a tube in place prior to sealing of the glass of the dome about the top lead, parts being shown in section.

Fig. 3 is a section on the line 3—3 of Fig. 2 looking upward with parts of the tube broken away to better expose top lead centering parts of the new device, and

Fig. 4 is a perspective view of a preferred embodiment of the wire guiding attachment.

Referring to the drawings with greater particularity and with immediate reference to Fig. 1, there is diagrammatically illustrated part of a sixteen position electron bulb sealing machine which functions to seal the bases of bulbs to stems or wafers which support the tube electrodes in proper spaced relationship to one another. For each machine position there is a tube peg for supporting the assembled parts of a tube and a cooperating head for centering the bulb during the time the bulb is being fused to the stem and while the top lead is sealed in the dome of the bulb. The heads and pegs are

2

all indexed about the machine, both heads and pegs rotating together at all stations except at station No. 16 which is the unloading station, station No. 1 which is the loading station, and station No. 2 at which the operator may adjust tube parts. In the diagram, the bulb is designated as 10 and the wafer stem with its electrode mount is indicated at 12. As an example, a type of electron tube is selected which comprises an anode 14 to which is welded a long bent lead-in wire 16, this lead-in wire extending through a preformed opening 18 within glass collar 20 formed on the dome 22 of the bulb. Prior to this invention, the operator, when loading the tube on a sealing peg 24 at the first or loading position of the machine, essayed to center the wire 16 within collar 20 by manual operation, but was not always successful. With the device of this invention no such manual centering is necessary, as will be made clear. In the operation of the machine, after loading the machine at station No. 1, the machine indexes, and the bulb and stem assembly 20 are lifted by reason of cams (not shown) acting on the pegs, bringing the tube nearer to the head. At station No. 2 the operator still has an opportunity to position parts on the peg. At station No. 3 the tube assembly is raised to an elevation such that the bulb is positioned centrally 25 of the stem assembly by a pair of arms 26 mounted on the head 28 of the machine. It should be noted that the bottom of the bulb rests on top of the stem assembly which keeps the bulb upright and the arms will assist in centering the bulb on the assembly. At this station the lead-in 16 is not yet centered by the machine. However, at this station rotation of the peg and head is initiated and pre-heating flames are applied to the juncture of the glass bulb and wafer. All of the mechanisms operating on the tube at stations No. 1 to No. 3 are old in the art and therefore no further description of the machine as to these features is deemed to be necessary herein. At station No. 4 a change in the mode of treatment of the sealing in of the lead-in wire does take place. At this station, as is conventional, the tube peg is raised to its maximum height bringing the bulb 10 well in between the centering arms 26. Here the wire 16 enters a novel element attached to the head, the same comprising a thimble 30 in the form of a conical guide provided with a central aperture through which the lead-in wire 16 extends. This guide centers the wire within the collar 20. At this station, as is conventional in the art, further preheating fires play on the bulb and wafer. At subsequent stations, preheating and pin point fires play on the bulb both at the bulb-wafer juncture and at the juncture of the glass collar 20 and the lead-in wire 16. Toward the final index stages of the machine, annealing fires are played on the seals while the peg lowers with its sealed tube. Usually at the station penultimate to unloading (station No. 15), no fires are played on the bulb but it is still revolved to allow the tube to set to symmetrical shape and to cool the same. At positions No. 14 and No. 15, it is no longer necessary to hold the lead-in wire in position since the seal of bulb dome to wire has already been effected. The sealed bulb and stem with sealed in anode lead-in wire is removed at station No. 16. Subsequently a cap is slipped over the end of the wire 16, adhered to the bead formed at the lead-in seal and soldered to the lead-in wire, as is customary in the art.

A specific means employed to center the lead-in wire is illustrated in Figs. 2, 3, and 4. In these figures there is shown at 28 one of the rotatable heads of the sealing machine, the same being supported by one of the machine's head supporting arms 32, the head being rotated by a chain mechanism 33 in housing 34 driving a shaft 36 to which the head 28 is fixed as by a bulb 38. The head is conveniently in the form of a spider with three

fingers 40 in which are fixed posts 42, 44, and 46, respectively. These posts are supplied for such affixations thereto as may be desired. In this embodiment post 42 has suitably affixed thereto the arms 26. One of these arms indicated as 48 in Figs. 2 and 3, is fixedly secured to post 42 by a hex nut 50. The other arm is suitably rotatably mounted on the post and is provided with a bulb engaging roller 54, this arm being spring pressed toward the arm 48 by a spring 56 having one end operating on an extension 58 from arm 52 and anchored at its other end to a pin 60 extending from a finger 40. No novelty is claimed as to the use of these bulb centering arms per se, since they are part of the prior art. However, as the bulb, seated on the peg 24 is lifted up, the dome of the bulb slides against the fixed arm end 48 while the arm 52 yields so that the roller 54 presses the bulb lightly against the end 48. These arms serve to center the bulb so that the lead-in centering device when centering the wire with respect to the longitudinal axis of the tube will also center it with reference to the longitudinal axis of the bulb.

The lead-in centering device is supported from a plate 62 provided with holes 43 and 47 to snugly embrace the posts 42 and 46 and clamped to the posts by cap screws 64 or the like. The plate has an arcuate recessed portion 66 adapted to surround the hub portion of the head 28 and a positioning recess 68 at the rear edge of the plate. Positioned by this recess is a vertical support bar 70, which is provided at the upper end with an elongated slot 72 through which a screw is passed and threaded 30 into the rear edge of the plate to hold the bar in selected vertical position in accordance with the height of the upper end of the lead-in wire to be guided. The bar is furnished at the lower end with an enlarged foot 74 provided with a recess to position a guide holding cantilever 76, this cantilever having a slot 78 at its rear end through which a screw 80 is passed to adjustably position the cantilever. At the front end of the cantilever is a bore accommodating the thimble 30. The thimble 30 is circular in horizontal cross section with a flange 82 40 engaging the lower surface of the cantilever, and held in the bore by a set screw 84 or the like. The interior of the thimble has an upwardly tapering conical opening 86 terminating in an opening 88 through which the lead wire 16 is passed. The hole in the thimble is centered 45

over the center of the peg associated with the head on which the guide is mounted. In this manner and by the aid of the guide and the bulb centering arms 48 and 52 it is possible to insure proper coaxial arrangement of the wafer stem, mount, bulb and top lead-in before sealing parts together.

Having thus described the invention, what is claimed is:

In a machine for sealing leads into a bulb and wherein the machine has a rotatable head and also a peg for rotatably supporting and vertically moving an assembly of wafer stem with its electrode mount and a bulb, the mount having a lead supported by an electrode element within the bulb which lead extends loosely through a central opening in the top of the bulb, means including bulb engaging arms mounted on the head for centering the bulb with respect to the wafer stem, the improvement comprising means for centering the lead with reference to the bulb opening, said last means comprising a support mounted on said head and rotatably therewith and with reference to which the peg is vertically movable, and an axially apertured conical element fixedly supported by the support in a position axially of the longitudinal axis of the rotatable head and at all times above the bulb engaging arms, with the conical element tapering upwardly to guide the lead into the aperture of the conical element when the assembly approaches the head.
